UNITED STATES PATENT OFFICE.

WESLEY GROFF NICHOLS, OF CHICAGO HEIGHTS, ILLINOIS, ASSIGNOR TO AMERICAN MANGANESE STEEL COMPANY, OF CHICAGO, ILLINOIS, A CORPORATION OF MAINE.

PLACER-DREDGE TUMBLER.

1,229,313.

Specification of Letters Patent. Patented June 12, 1917.

Application filed October 2, 1915. Serial No. 53,767.

To all whom it may concern:

Be it known that I, WESLEY G. NICHOLS, a citizen of the United States, and resident of Chicago Heights, county of Cook, and 5 State of Illinois, have invented certain new and useful Improvements in Placer-Dredge Tumblers, of which the following is a specification.

In dredges the dredging is usually done 10 by a chain of buckets fastened together in a suitable manner and adapted to move over a boom or leg. These buckets weigh two to four thousand pounds apiece and, as a chain is sometimes composed of as many as eighty 15 of these buckets, there results a very cumbersome and heavy conveyer.

The boom or leg is provided with rollers or tumblers, one at each end of the boom, over which the chain of buckets moves. The 20 top tumbler is positively driven which imparts motion to the chain. The lower tumbler is freely revoluble and is mounted on the bottom of the boom. These rollers weigh from nine hundred to twenty-six thousand 25 pounds apiece, so that the matter of breakage and consequent delay therefrom is of vital importance. Heretofore the lower tumblers have been made from a single casting and are substantially spool-shaped with 30 proper flanges for guiding the chain of buckets. It sometimes happens in dredging that rocks, etc., are struck by some of the buckets on the chain thereby causing a sharp sidewise movement of the chain, which results in the breaking of one of the flanges 35 of the tumbler. Oftentimes the flanges wear off and it is necessary to stop the operation of the dredge until a new casting can be secured.

40 One of the largest items of expense in the casting of manganese steel is the loss from faulty castings, either in the mold or in subsequent treatment. Furthermore, such castings may have defects not apparent to the eye which may result in failure in service with consequent loss to the manufacturer by whom it must be replaced. An object in 45 the present construction is to reduce the liability to the production of faulty castings 50 by so designing the parts that shrinkage strains are reduced, this result being secured partially by forming the usually huge casting in two portions—the outer or flange portion, and a hub or drum portion, the 55 drum portion adapted to fit within the

flange portion with provisions for holding the parts from disengagement. As it is necessary to make the connection water-tight I prefer to shrink the flange portion onto the drum portion, thus removing all chance of 60 separation. If the flange member of my improved tumbler be broken or worn out, it is necessary to replace same by cutting off the flange member of the drum with the aid of oxyacetylene flame, or some other 65 cutting means, and to shrink on a new flange member. It will readily be seen that the drum can be used indefinitely and refitted many times with spool members—a construction which will greatly reduce the time 70 consumed in breakage and will reduce the cost of repairs. I prefer to make the spool and drum members from manganese steel, thereby furnishing a tumbler offering the greatest resistance to wear and breakage. I 75 also prefer to form the drum member with imperforate ends having its interior cored out, as I secure a lighter casting without sacrificing strength.

Further advantages will be seen by referring to the drawings wherein:

Figure 1 is an end view of a tumbler embodying my invention, showing a drum member in place and the flange member.

Fig. 2 is a section on the line 2—2 of 85 Fig. 1.

Fig. 3 is a section on the line 3—3 of Fig. 2.

Fig. 4 is a side view of the preferred form of my cored out drum.

The numeral 10 indicates the flange member having the usual recess for a chain and provided with a central aperture. 11 represents the drum member formed with imperforate ends and having slots 12 in its 95 surface. An aperture 13 is provided in the drum 11 for the reception of the shaft on which the tumbler is mounted. Extending part way inwardly from the ends of the drum 11 are sleeves 14 formed for the purpose of providing greater bearing surface 100 on the shaft (not shown) which extends through the tumbler. Longitudinally-extending ribs 15 are formed within the drum for the purpose of strengthening the surface 105 of the drum and also for supporting the sleeve members 14. In order to secure the drum against endwise and rotative movement when put in the flange member 10, I provide on the interior of the flange member 110

lugs 16 and in the surfaces of the drum 11 I provide keyways 17 which are adapted to register with the lugs 16 when the drum is inserted in the flange member. For the purpose of locking the drum within the flange I enlarge the forward ends of the keyways 17 as best shown at 18 in Fig. 4 so that when the drum is inserted and the end of the keyway abuts against the lugs 16, by turning the drum slightly it will be held against endwise movement by engagement of the lugs 16 with the enlarged end portions of the keyway. I provide fillers 19 to close the keyways 17 after the drum is in place. Before the joining of the drum in the flange I heat the flange member to expand it in order that it may shrink onto the drum. I thus make a water-tight connection all the way around. This shrinking also prevents any endwise or rotative movement of the drum and is sufficient for the prevention of such movement, although I prefer to employ the lugs 16 and the keyway 17 as described.

I do not confine myself to the precise form shown, but consider the form admissible of modifications, and such modifications as come within the scope of my claims I consider as being within the spirit of my invention.

30 I claim:

1. A dredge tumbler of relatively great size and weight, comprising, in combination, a spool and a drum, said drum being constructed in the form of a skeleton cylinder, the peripheral surface of which is interrupted by spaces, said drum and spool having interengaging lugs and recesses, and a key for positively locking said parts against relative movement, substantially as described.

2. In a dredge tumbler, the combination of a hollow cylindrical shell having an axial sleeve providing a shaft opening, the peripheral surface of the cylinder being interrupted by a series of spaces, the shell being provided with keyways on its surface, and a spool having an axial opening and provided with lugs projecting into said opening, said lugs being adapted to engage with said keyways, and means for permanently securing said spool and drum in engagement.

3. In combination, a spool and a drum, the drum slidably engaging with said spool, said drum being cylindrical in shape and provided with a central aperture therethrough, said drum having otherwise imperforate ends and being provided with slots

in its periphery, and a cored interior portion, the surface between said slots being provided with keyways having enlarged ends, said spool being provided with a cylindrical central aperture, and with lugs on the surface thereof engaging with said keyway in said drum, substantially as described.

4. A dredge tumbler of relatively great size and the principal component parts of which are composed of alloy steel, comprising in combination a one-piece spool and a one-piece skeleton drum upon which said spool is adapted to be permanently mounted, the walls composing the spool being of substantially uniform thickness at all points, said drum having an axial hub which is interrupted at a point intermediate its ends, and means for permanently uniting said drum and spool, substantially as described.

5. A drum, a spool mounted thereon, said spool having an aperture and being provided with lugs, said drum being provided with keyways engaging with said lugs and interlocking therewith, said drum having an axial shaft opening and provided with otherwise imperforate ends and a skeleton body and slidably insertible in said spool, substantially as described.

6. A dredge tumbler of relatively great size and weight and the principal component parts of which are composed of alloy steel, comprising in combination a one-piece spool and a one-piece skeleton drum upon which said spool is adapted to be permanently mounted, the walls composing the spool and drum being of substantially uniform thickness at all points, said spool being shrunk onto said drum in order to permanently unite the parts, substantially as described.

7. A dredge tumbler of relatively great size and weight, comprising in combination a one-piece spool composed of alloy steel and a one-piece skeleton drum upon which said spool is adapted to be permanently mounted, the walls composing the spool being of substantially uniform thickness at all points, whereby shrinkage strains are avoided in the casting of the article, said spool being shrunk onto said drum, said drum and spool having interengaging lugs and recesses for positively preventing relative rotation of said spool and drum, substantially as described.

WESLEY GROFF NICHOLS.
